UNITED STATES PATENT OFFICE.

GEORGE CORBION, JR., OF PHILADELPHIA, PENNSYLVANIA.

SIPHON-BOTTLE.

SPECIFICATION forming part of Letters Patent No. 578,094, dated March 2, 1897.

Application filed September 7, 1895. Serial No. 561,860. (No model.)

To all whom it may concern:

Be it known that I, GEORGE CORBION, Jr., a citizen of the United States, residing in the city and county of Philadelphia and State of Pennsylvania, have invented certain new and useful Improvements in Siphon-Bottles, of which the following is a full, clear, and exact description, reference being had to the accompanying drawings, forming a part of this specification.

This invention relates to bottles, having reference more especially to that class of bottles termed "siphon," in which aerated or carbonated waters are contained, my object being mainly to provide a construction whereby the bottles may be more expeditiously and effectively charged than heretofore, whereby their uses may be extended to a wider range of liquids, and whereby the bottles may be readily and thoroughly cleansed without the necessity of removing the siphon-heads therefrom, as will be hereinafter particularly described and claimed.

In the annexed drawings, Figure 1 is a longitudinal central section of a siphon-bottle embodying my invention in a simple and efficient form. Fig. 2 is a plan thereof. Fig. 3 is a vertical section of the siphon-head as on the line $x-x$ of Fig. 2. Fig. 4 is a partial longitudinal central section of a modification.

A designates a bottle of proper shape and size for its intended purpose. The bottle herein shown is similar in form to an ordinary siphon-bottle, excepting that it is provided with an opening a in the center of its bottom and with a valve a' to seal the opening, as will hereinafter appear.

Screwed to a split collar on the neck of the bottle or otherwise secured to the bottle is a siphon-head B, which is provided with the usual discharge-nozzle b and with a depending tube b' , that leads therefrom to the bottom of the bottle, or nearly so. The head is also provided with a suitable release-valve b^2 , (preferably of the character below described,) that opens or closes the communication between the nozzle and the tube, as desired. In the top of the head is formed a chamber b^3 , that communicates with the interior of the bottle by means of channels b^4 on the respective sides of the valve-chamber. Surmounting

the head is a screw-collar b^5 , to the inner edge of which is fitted an annular gasket b^6 , while within the chamber is contained a seal b^7 , preferably a spherical ball, which is adapted to be seated against the gasket by the pressure of the confined gases within the bottle, so as to hermetically seal the opening.

In the side of the siphon-head, at a point below the release-valve, is a vent or passage b^8 , which is normally closed by a spring-controlled valve b^9 , the stem of which projects exteriorly of the head, as seen, whereby pressure may be readily applied to the valve to open the passage for a purpose below explained.

Siphon-bottles as heretofore constructed have been filled upside down by especial apparatus, through and by way of the discharge-nozzle and the inner tube, thereby requiring to fill or charge the bottle about double the pressure required to discharge it. This is owing to the necessarily small delivery-channel, which, moreover, precludes the use of siphon-bottles for beers or any beverages containing syrups, compounds, or foams, and, in consequence, the use of the bottles is restricted to soda, artificial or natural spring and mineral waters that do not foam under pressure. By the construction herein these objections are obviated, since in order to fill the bottle (assuming the release-valve to be closed) it is merely requisite to introduce the beverage by way of the chamber b^3 , the valve therein, when the bottle has been charged, being automatically pressed against its seat by the pressure of the confined gases, as above mentioned.

Another objection to the prior construction is that in order to effect the escape of the compressed air within the bottle during the charging process it has been necessary to cease the operation and permit the air to escape by way of the tube and nozzle, and such escape being more or less uncertain bottles of extraordinary strength were required. By my construction, however, the "snifing," as it is termed, may be expeditiously and effectively carried on during the actual charging of the bottle, the valve b^9 being merely pressed from time to time to open the vent or passage.

Another objection to the previous construc-

tion is that the bottle cannot be washed out without the necessity of removing the siphon-head, which is only done with considerable skill, difficulty, and great waste of time. This 5 objection is avoided by the bottom opening a^1 . The valve for this opening comprises an elongated head provided with a gasket a^2 thereon, the head being constructed to fit the opening and the gasket to bear upon the edge of the 10 latter. The valve normally enters the opening, and the pressure of the confined gases on the valve insures an effectual sealing of the opening.

In some instances, particularly where an 15 ordinary siphon-head is employed, the bottle may be charged by way of the bottom opening, the snifting operation thus being effected through the manipulation of the release-valve.

20 If desired, the bottom of the bottle may comprise a detachable metal cap or base provided with a central opening therein.

As to the release-valve b^2 , while it may be of the usual construction, that is, longitudinally reciprocative in respect to the bottle, I 25 prefer to use with my improved siphon-head a horizontally-reciprocative valve that is operated by means of a spring-controlled thumb-lever b^{10} on the head. Where the valve is 30 vertically reciprocative, it is subjected directly to the pressure of the confined gases, and hence a comparatively powerful spring is required to counteract the pressure; but where the valve is transversely movable, as 35 in this instance, the tendency of the gases to open the valve is avoided, and hence a comparatively light spring is required, and in consequence slight manual power is required to open the valve.

40 In Fig. 4 is shown a slight modification of the invention wherein the chamber b^3 in the top of the siphon-head communicates by a single direct passage with the interior of the bottle, the seal b^7 being a disk valve which is 45 yieldingly held to its seat by means of a suitably-disposed spring b^{11} and the release-valve being a rotary instead of a sliding one. In this construction the snifter-valve is shown as applied directly to the body of the bottle 50 instead of to the siphon-head.

Obviously the invention may be otherwise modified to meet particular requirements.

I claim as my invention—

1. A siphon-head provided with a discharge-nozzle having communication with the interior of the bottle to which the head may be applied, a manually-operated release-valve to control such communication, an open charging-chamber formed in said head above the 55 nozzle, a passage or passages adapted to provide communication between said chamber and the interior of the bottle, a valve-seat at the mouth of said chamber, and a valve or seal therefor, substantially as described.

60 2. A siphon-head provided with a discharge-nozzle having communication with the inter-

rior of the bottle to which the head may be applied, a manually-operated release-valve to control such communication, an open charging-chamber formed in said head above the 70 nozzle, a passage or passages adapted to provide communication between said chamber and the interior of the bottle, a valve-seat at the mouth of said chamber, and a seal contained in said chamber and adapted to be seated by the pressure of the confined gases within the latter, substantially as described.

65 3. A siphon-head provided with a discharge-nozzle, a depending tube, a manually-operated release-valve that controls the communication between said nozzle and tube, an open charging-chamber formed in said head above the 80 nozzle a passage or passages to provide communication between said chamber and the interior of the bottle to which the head 85 may be applied, a valve-seat at the mouth of said chamber, and a seal contained in said chamber and adapted to be seated by the pressure of the confined gases within the bottle, substantially as described.

90 4. A siphon-head provided with a discharge-nozzle, a depending tube, a manually-operated release-valve that controls the communication between said nozzle and tube, an open charging-chamber formed in said head above the 95 nozzle, a passage or passages adapted to provide communication between said chamber and the interior of the bottle to which the head may be applied, a valve-seat at the mouth of said chamber, a seal contained in 100 said chamber and adapted to be seated by the pressure of the confined gases within the bottle, and a spring-actuated snifter-valve below said chamber, substantially as described.

105 5. A siphon-head provided with a discharge-nozzle, a depending tube, a manually-operated release-valve that controls the communication between said nozzle and tube, an open charging-chamber formed in said head above the 110 nozzle, a passage or passages adapted to provide communication between said chamber and the interior of the bottle to which the head may be applied, a screw-collar on said head, an annular gasket fitted to the inner 115 edge of said collar, and a spherical ball contained in the chamber and adapted to be seated against the gasket by the pressure of the confined gases within the bottle, substantially as described.

120 6. A siphon-head provided with a discharge-nozzle, a depending tube, a manually-operated release-valve that controls the communication between said nozzle and tube, an open charging-chamber formed in said head above the 125 nozzle, a passage or passages adapted to provide communication between said chamber and the interior of the bottle to which the head may be applied, a screw-collar on said head, an annular gasket fitted to the inner 130 edge of said collar, a spherical ball contained in the chamber and adapted to be seated

against the gasket by the pressure of the confined gases within the bottle, a vent or passage in the side of the head, at a point below the release-valve, and a spring-controlled valve fitted to said vent or passage, the stem of said valve projecting exteriorly of the head, substantially as described.

In testimony whereof I have hereunto affixed my signature in the presence of two subscribing witnesses.
